CLAIM

The ornamental design for a portion of a computer screen with a graphical user interface as shown and described.

DESCRIPTION

The file of this patent contains at least one drawing/photograph executed in color. Copies of this patent with color drawing(s)/photograph(s) will be provided by the Office upon request and payment of the necessary fee.

The FIGURE is a front view of the portion of a computer screen with a graphical user interface, showing the new design.

The broken line showing the computer screen is included for the purpose of illustrating portions of the article and forms no part of the claimed design.
